United States Patent

Des. 242,259
Patented Nov. 9, 1976

242,259

LOUDSPEAKER

Burton A. Babb, 6618 Briarhaven Drive 75240, and
Elbert M. Hubbard, 6930 Elmridge 75240, both of
Dallas, Tex.

Filed Feb. 4, 1974, Ser. No. 439,256

Term of patent 14 years

Int. Cl. D14—01
U.S. Cl. D26—14 G

FIG. 1

FIG. 2

FIG. 3

FIG. 4

FIG. 5

FIG. 6

FIG. 7

FIG. 1 is a perspective view of a design for a loudspeaker embodying the design of the present invention;

FIG. 2 is a front elevational view of the loudspeaker of FIG. 1;

FIG. 3 is a side elevational view of the loudspeaker of FIG. 1;

FIG. 4 is a plan view of the loudspeaker of FIG. 1;

FIG. 5 is a rear view of the loudspeaker of FIG. 1;

FIG. 6 is a perspective view similar to FIG. 1 showing another loudspeaker embodying the design of the present invention which is two of the components of FIG. 1;

FIG. 7 is a perspective view of still another loudspeaker embodying the design of the present invention which utilizes four of the audio components of FIG. 1.

We claim:

The ornamental design for a loudspeaker, as shown.
